CARGO HOOK

Filed Feb. 26, 1923

INVENTOR

Louis Cot

BY

Paul M. Klein

ATTORNEY

UNITED STATES PATENT OFFICE.

LOUIS COT, OF BROOKLYN, NEW YORK.

CARGO HOOK.

Application filed February 26, 1923. Serial No. 621,346.

To all whom it may concern:

Be it known that I, Louis Cot, subject of Spain, and resident of 50 Sackett Street, Brooklyn, in the county of Kings and State of New York, have invented certain new and useful Improvements in Cargo Hooks, of which the following is a specification.

This invention relates to hooks in general, and particularly to the kind employed for suspending cargo from derricks or other hoisting implements.

The main objects of the present invention is to provide a simple inexpensive and safe device, by means of which a load may be either transferred from one hoisting device to another or from a hoisting device to a place of repose and permitting the release of the load by relaxing the cable by which the load is suspended and by reversing the position of my device.

In order to better understand the working principle of my device, it is necessary to refer to the similar device now in use and consisting mainly of gripping claws or U shaped hooks, which are adapted to suspend a load, and manually operable releasing means by way of which the suspension hooks may be opened, thus permitting the load to drop. The greater the load the harder it becomes to release such devices. Usually a line is attached to the release and the helper is to pull thereon until the device is opened.

Moreover most of the releasing devices keep the hooks closed only as long as the load is suspended from the latter, but in the event that the load would be transferred to another hoisting device it is hard to operate the release.

From the foregoing it will be evident that such devices are not only impractical but even dangerous in operation. My invention is designed to overcome the aforementioned disadvantage by employing an entirely new principle of operation.

The advantages of my device will be more fully apparent from the following description and accompanying drawings, forming part of this specification, but representing only one of the many possible embodiments of my device, and in which:

Figure 1 is the side elevation of my device partially in section, in closed position while suspending a load.

Figure 2 is a side elevation of my device

partially in section and showing it reversed in open condition.

Figure 3 is a partial end view seen from lines 3—3 of Figure 1.

Referring to the drawings numeral 10 denotes the load suspension member, which is generally of a dog-like shape and provided with a depression 11 between fingers 12 and 13.

Finger 12 is reduced at its upper portion 65 as indicated at 14. The lower end of member 10 has a reduced extension 15, provided with an eye 16, which passes a pin 17 forming a hinged connection with locking member 18. Locking member 18 is provided 70 with a T-shaped gravity head 19 having a flute-like recess 20, adapted to register with the reduced extension 14 of the load suspension member 10. At the outer end of the head there are provided one or more guide 75 apertures 21 and 22 the purpose of which will be explained later.

The leg 23 of the locking member 18 is also perforated at 24 and 25. At the lower end of the leg 23 there is provided a recess 80 26, in which freely swings extension 15 of load suspension member 10. At the extreme end of leg 23 there is provided a rest or stop 27, which limits the outswing of member 10.

85 Finger 13 of member 10 provides a stop for the latter when bearing against leg 23 of member 18. Below finger 13 there may be provided an eye or hook indicated at 28, for receiving a single flexible element indicated at 29 and which is adapted to close and keep the two members in closed position when desired, but permitting an opening of the members when it is necessary. When such single flexible element 29 is employed it 90 passes through aperture 24 of leg 23 and through aperture 21 to head 19. Instead of the single flexible member 29 there might be employed a double flexible element 30, in which case a fastening lug 31 provided 95 in the body of member 10, is employed for attaching flexible element 30. In this case flexible element 30 passes through apertures 21 of the head 19 and 24 and 25 of the leg 23, and back through aperture 22 of head 19. 100 However, any other suitable arrangement of fastening the flexible element 30 may be 105 employed.

In Figure 1 my device is shown in closed position and suspended by means of flexible 110

element 29 and supporting a load indicated by the broken lines I.

Assume that my device is now attached to a crane and the load I is held by convenient means within hook-shaped depression 11. Now the load may be transferred from one place to the other without difficulty and with absolute safety.

When now the suspension means supporting the load is engaged by another hoisting device and pulled up in the direction shown in Figure 2, by broken lines II, while at the same time flexible element 29 is slackened, my device will be turned to the position indicated in Figure 2. In this position the gravity head 19 drops down and disengages finger 12 of member 10, thereby opening my device and releasing the suspension means of the load and permitting the latter to be now freely suspended by the other hoisting device.

The same manner of operation applies for instance, in the case where cargo is to be lifted into the hull of a ship, with the exception that a second hoisting device is not employed, but instead a helper pulls the sling suspending the cargo to one side until the reversal of my device has taken place and member 10 released.

It is evident that while I have shown a specific form of my invention in the drawings, be it understood that various designs may be made, based on the same principle and without departing from the broad scope of my idea, for which I claim:

1. A cargo hook, comprising a load receiving member, a locking member and means for keeping the former member in locking engagement with the locking member when the device is in one position, and permitting the release of said load receiving member when the device is in another position.

2. A cargo hook, comprising a load supporting member, a gravity operated locking member and means for keeping said members in closed relation when desired. 45

3. A cargo hook, comprising a load supporting member, a gravity operated locking member, and flexible means for keeping said members in closed relation and permitting their opening, when desired. 50

4. A cargo hook, comprising a load supporting member, a gravity operated locking member hingedly associated with said former member, a flexible element engaging said load supporting member and passing through said locking member and adapted to keep said members in closed relation and permitting their opening when desired. 55

5. A cargo hook, comprising a load supporting member, a gravity operated locking member, the former hingedly associated with the latter member, a flexible element engaging the load supporting member and passing through said locking member, means provided in said former member for facilitating the fastening thereto of said element, and means provided in said locking member for guiding said element. 60 70

6. In a cargo hook, a load suspending member, a locking member, the former hinged with the latter and provided with means for receiving a flexible element, the said locking member provided with guide means for a flexible element and a gravity head adapted to change the position of the device, and a flexible element connecting the two members and adapted to either keep them in interlocking position or permit 75 their opening when desired.

Signed at New York, in the county of New York and State of New York, this 10th day of February, A. D. 1923.

LOUIS COT.
